UNITED STATES PATENT OFFICE.

JOHN A. MAHNK, OF LOS ANGELES, CALIFORNIA.

IDENTIFICATION BUTTON.

Application filed March 22, 1926. Serial No. 96,552.

My invention is an identification device preferably arranged in the form of a button.

An object of my invention is an identification device in the form of a hollow button 5 adapted to be attached to a person's clothing, the button forming a housing for an identification mark.

Another object of my invention is to form the identification mark or device in a foldable strip of paper or other suitable material, the folds being shaped to neatly fit within the button type of device so that a considerable amount of information as to the wearer may be enclosed in a relatively small place.

15 A further object of my invention is to form a button structure with a fastener so that it may readily be attached to a person's clothes and if desired, the button may be utilized for the purpose of a button.

20 In constructing my invention I form a hollow receptacle preferably of circular shape and merely large enough to contain a folded strip of paper or the like containing identification information. The strip of paper is preferably secured to a bar or hook 25 secured to the base of the housing or button casing and the strip of paper is formed with a series of curves or indentations on the top and bottom so that it may be folded at the 30 innermost meeting place of the curves and neatly packed within the button.

Another feature of my invention is a pin 35 having a holder attachable and detachable thereon so that the pin may be inserted through clothing or the like and the button firmly attached to such clothing.

My invention will be more readily understood from the following description and drawings, in which;

40 Figure 1 is a perspective view of my identification button open, showing the strip of paper with the identification information thereon;

Fig. 2 is a face view of the button;

45 Fig. 3 is a side elevation;

Fig. 4 is an inside view with the paper strip removed;

Fig. 5 is a section on the line 5—5 of Fig. 2.

50 The button structure 1 comprises a hollow receptacle or the like having a base 2 preferably circular with an upstanding rim 3. This rim is preferably stepped having a shoulder 4. The cap or cover 5 is preferably domed slightly, this being partly for appearance's sake, and having a flange 6 fitting

over the rim 3 and abutting against the shoulder 4. Thumb nail notches 7 allow the detaching of the cap from the base, the structure preferably being sufficiently tight that 60 it will not readily open.

A bar 8 having a straight central part 9 and ends 10 secured to the base portion of the button and preferably lies close to the base. The identification strip 11 is preferably formed of paper or other suitable material on which may be written and which will not deteriorate. This strip preferably has a tab 12 which may be looped around the central part of the bar and glued thereto. 70 The strip is formed with a series of curves 13 having indentations 14, the strip being adapted to fold on the lines indicated by 15 joining the opposite indentations.

The identification strip may have such information as the person's name indicated by the numeral 16, his address as indicated by the numeral 17, telephone number 18 and any other suitable directions to be utilized if the wearer should be unconscious or 75 injured or if worn by a child to give directions as to getting the child to its home if the child becomes lost.

A pin 20 is secured to the base of the button and preferably extends directly at right 80 angles to the base. A thumb piece 21, having a finger grip 22 to allow loosening thereof, is attachable to the pin. Therefore when the pin is inserted through the fabric 23 indicating part of a person's clothing the 85 thumb piece 21 may be secured over the end of the pin and hold the button securely in position. The button may, if desired, have the words identification button or the like 90 printed or indented on the top, or the face 95 of the button may be made ornamental if desired.

It will be apparent that the device is of a simple character and that it could be worn in an inconspicuous place and yet be readily 100 found should the wearer through any cause become unconscious or unable to help himself, or in the case of being worn by a child, the child should be taught to call attention to the button should it become lost; therefore aiding in locating the home of the child.

105 It will be apparent that my device might be used for other purposes as for instance gift devices or the like, and that the general construction and specific details could be 110 considerably changed to adapt it for different purposes. However, such changes and

modifications would be within the spirit of my invention as set forth in the description, drawings and claim.

Having described my invention, what I claim is:

An identification device comprising in combination a hollow receptacle having a base with an upstanding annular rim, a U-shaped bar having its ends secured to said rim at points within the same semi-circular portion thereof, said bar lying adjacent and substantially parallel to said base, the bend of said U-shaped bar extending in substantially diametrical relation to said identification device, a strip of paper secured to said bar, said strip of paper comprising an elongated piece of flat material and being formed in sections adapted to be folded one upon the other, said sections having curved edges and straight sides, the fold occurring along said straight sides, the longitudinal width of said sections being substantially smaller than the diameter of said identification de-

vice, and the transverse width of said sections being substantially the same as the diameter of said pin, whereby said sections when folded, may be inserted within said pin snugly, and arcuate pockets will be formed between the upstanding rim and the folded paper, a tab on one end of said paper adapted to be folded over said U-shaped bar, said tab being of a width equal to the radius of said identification button, a cover having a flange extending over said rim, and notches in said flange whereby said cover may be removed from said base, a pin secured to the base projecting substantially at right angles thereto, and a thumb piece adapted to be inserted over said pin to hold the identification button in place on a garment, said cover presenting a substantially concavo-convex surface, whereby said identification device may simulate a button.

In testimony whereof I have signed my name to this specification.

JOHN A. MAHNK.
